RAYMOND C. HAISS, OF NEW YORK, N. Y., ASSIGNOR TO GEORGE HAISS MANUFACTURING CO. INC., OF NEW YORK, N. Y., A CORPORATION OF NEW YORK

WAGON LOADER AND EXCAVATOR

Application filed April 29, 1929. Serial No. 358,818.

This invention relates to machines of the general type shown and described in my application No. 352,196, filed April 3, 1929, Wagon loaders and excavators, and is directed particularly to a modified form of digging and feeding mechanism.

The primary object of the invention is to provide a novel digging and feeding mechanism by which the operation of such a machine as that to which this invention relates may be satisfactorily carried out under adverse conditions, as when, for example, the material to be handled is of such a nature as to require loosening or breaking up thereof before it can be effectively acted upon by the material-propelling means.

To the above end the present invention contemplates the use of a plurality of rotatable digging elements for loosening or breaking up firmly packed and even frozen material, such as earth, sand, gravel and the like in combination with material-propelling means comprising screw-like members and more specifically suitably supported screw-like ribbons for moving the loosened or broken-up material into the path of the conveyor by which such material is picked up and elevated to a truck or other vehicle adapted to receive the same.

Other objects and advantages of the invention will become apparent from the following description, taken in connection with the accompanying drawings, in which—

Figure 1 is a side elevation of the pick-up end of a wagon loader and excavator embodying this invention; Figure 2 is a plan view of the parts shown in Figure 1; and Figure 3 is an enlarged detail view showing in side elevation one of a plurality of digging elements and one of a plurality of supporting arms for the material-propelling screw-like ribbons.

Loaders of the type above mentioned include a frame 10, adjustably mounted upon a traction device (not shown) by which the machine may be propelled from place to place and crowded at slow speed toward and into the material to be loaded, there being a power unit, such as an internal combustion engine (not shown) employed as a driving

means for the traction device as well as for the bucket conveyor 11. This conveyor includes a plurality of buckets 12, carried by a pair of chains 13, passing over sprockets of which the lower sprockets 14 only are shown, these lower sprockets being secured to a shaft 15 intermediate the ends of the shaft, and the shaft 15 being journalled at 16 in the lower end of the frame 10 and extending transversely of the machine. It will be understood that the driving connection between the power unit and the conveyor chains 13 which drive the shaft 15, is such that this shaft is rotated in the direction of the arrow A in Figure 1.

Secured to the portions of the shaft 15 which extend from each side of the journal boxes 16, are a plurality of sets of digging elements or picks 19 and radially disposed arms 20, to the outer ends of the latter of which are secured material-propelling means comprising screw-like ribbons hereinafter more particularly described. From the drawings, particularly Figure 3, it will be seen that each pick is secured to an arm, and both are secured to the shaft 15 by means of bolts 21 which pass through holes in flanges 22 and 23 extending from the hub portions 24 and 25 of the picks and arms, respectively.

In the form of the invention herein shown, there are six picks at each end of the shaft 15, such picks being disposed at an angle of approximately 90° from their respective corresponding arms. It will be understood, however, that the number of picks may be varied and their angular relation to the respective arms may be changed without departing from the spirit of the invention. Moreover, while the picks are shown as being six in number at each end of the shaft 15, it is of course obvious that changes may be made in this respect also without departing from the invention. When the picks are arranged as herein shown, there will be four positions of impact to each rotation of the shaft 15. In so far as the picks at one end of the shaft are concerned, there will be two positions of impact where only one pick is entering the material being acted upon, 100

whereas for each of the remaining positions of impact there will be two picks entering the material at the same time. As to the picks at the other end of the shaft, there will likewise be two positions of impact where only one pick is entering the material and for each of the remaining positions of impact there will be two picks entering the material. In order that the impacts may be evenly distributed, when the number and arrangement of picks herein shown are employed, through 360° of rotation of the shaft 15, corresponding picks are disposed 180° apart. By thus arranging the picks at one 15 end of the shaft at 180° with respect to corresponding picks at the other end of the shaft, it follows that for each of the four positions of impact there will be three picks simultaneously entering the material to be loaded, 20 two of such picks being at one end of the shaft and the other of such picks being at the other end of the shaft for two positions of impact and two of such picks being at said other end of the shaft and one of such picks 25 at said one end of the shaft for each of the other two positions of impact. Inasmuch as this arrangement of picks is such that the same number of such picks enter the material being acted upon at each position of impact, 30 it is obvious that a relatively smooth operation of the machine with a lesser maximum power demand is made possible.

Secured to the outer ends of the arms 20 are material-propelling means, herein shown 35 as a pair of oppositely pitched screw-like members or ribbons 26 and 27, located at opposite sides of the conveyor. These material-propelling members are so disposed with respect to the digging elements as to act upon 40 the material, which is broken up or loosened by the digging elements as they are advanced or forced through the material, and to move such loosened or broken-up material towards and into the path of the conveyor buckets as 45 the machine progresses along the path of excavation, which is sufficiently wide to accommodate the usual traction mechanism by which the machine is propelled.

Regardless of whether the machine is employed in the handling of loose or compact material, the path of travel of the conveyor buckets is cleared by the buckets themselves, which, due to the provision of digging teeth, as shown, on the forward edges thereof, can 50 be forced forwardly and upwardly through the material with comparative ease. The path which is cleared by the buckets provides room to receive the material which is moved inwardly from opposite sides of the 55 conveyor by the material-propelling means as the machine advances toward and into the material to be loaded or excavated.

Although only one form of the invention is herein shown and particularly described, it 60 will be understood that certain other modi-

fications may be employed without departing from the spirit of the invention or the scope of the following claims.

What is claimed is:

1. A machine of the character described comprising a conveyor having buckets adapted to receive material at the pick-up end of the conveyor and elevate it to the discharge end of the same, a plurality of rotatable digging elements disposed at opposite sides of said conveyor at the pick-up end thereof and adapted to impart forwardly and upwardly directed impacts to the material, and rotatable screw-like members associated with said digging elements, the digging elements being arranged in advance of the corresponding parts of the screw-like members in the planes of rotation of the digging elements, said screw-like members being oppositely pitched for moving the material acted upon by the digging elements out of the path thereof and into the path of the conveyor buckets. 75

2. A machine of the character described comprising a conveyor having buckets adapted to receive material at the pick-up end of the conveyor and elevate it to the discharge end of the same, a rotatable shaft located at the pick-up end of said conveyor and projecting outwardly beyond opposite sides thereof, a plurality of digging elements carried by said shaft at opposite ends thereof and adapted to impart forwardly and upwardly directed impacts to the material, and rotatable screw-like members carried by said shaft and having parts adapted to operate upon material in the planes of rotation of the digging elements at the rear of such elements, said screw-like members being oppositely pitched for moving the material acted upon by the digging elements toward and into the path of the conveyor buckets. 90

3. A machine of the character described comprising a conveyor having buckets adapted to receive material at the pick-up end of the conveyor and elevate it to the discharge end of the same, a rotatable shaft located at the pick-up end of said conveyor and projecting outwardly beyond opposite sides thereof, a plurality of digging elements carried by said shaft at opposite ends of the said shaft and adapted to impart forwardly and upwardly directed impacts to the material, a plurality of radially disposed arms carried by said shaft at opposite ends thereof, and rotatable screw-like ribbons secured to the outer ends of said arms and adapted to operate upon material in the planes of rotation of the digging elements and at the rear of such elements, said screw-like ribbons being oppositely pitched for moving the material acted upon by the digging elements toward and into the path of the conveyor buckets. 105

4. A machine of the character described comprising a conveyor having buckets adapted to receive material at the pick-up end of 110

the conveyor and elevate it to the discharge end of the same, a rotatable shaft located at the pick-up end of said conveyor and projecting outwardly beyond opposite sides thereof, a plurality of digging elements and corresponding radially disposed arms carried at opposite ends of said shaft, said digging elements being adapted to impart forwardly and upwardly directed impacts to the material, rotatable screw-like ribbons secured to the outer ends of said arms and having parts adapted to operate upon the material previously acted upon by said digging elements, said screw-like ribbons being oppositely pitched for moving the material acted upon by the digging elements towards and into the path of the conveyor buckets, and a common attaching means for securing to said shaft each said digging element and its corresponding arm.

20 In testimony whereof, I have affixed my signature to this specification.
